(57) CLAIM

I claim the ornamental design for a multi-colored cabinet appliance interior, as shown.

DESCRIPTION

The patent or application file contains at least one drawing executed in color. Copies of this patent or patent application publication with color drawing(s) will be provided by the Office upon request and payment of the necessary fee.

The sole FIGURE is a perspective view of a multi-colored cabinet appliance interior.

The cabinet back wall, the left and right cabinet liners and the right front door liner are silver. The left door liner as well as the facie and solid portions of the crisper drawers and pantry drawers are gray. The trim on the top, front of the crisper and the trim on the top, front of the pantry drawer and the trim of the door bins are aluminum in color.
